MAURICE J. TOPP, OF MANLIUS, AND WILBUR G. MILLER, OF SYRACUSE, NEW YORK.

WILLOW STRIPPER.

Application filed April 25, 1918. Serial No. 230,664.

To all whom it may concern:

Be it known that we, MAURICE J. TOPP and WILBUR G. MILLER, citizens of the United States of America, and residents of 5 Manlius and Syracuse, respectively, in the county of Onondaga, in the State of New York, have invented new and useful Improvements in Willow Strippers, of which the following, taken in connection with the 10 accompanying drawings, is a full, clear, and exact description.

This invention relates to certain improvements in willow stripping machines, involving the use of a gripping device and a stripping device, one of which devices is movable relatively to the other to remove the bark lengthwise of the willow.

The main object is to provide a more efficient and expeditious means for removing 20 all of the bark from the willows from end to end without liability of mutilating the wood.

Another object is to simplify the construction and operation of machines of this character so that they may be installed and 25 operated by inexperienced labor and at a minimum cost.

A further object is to attach the gripping device to an oscillatory carrier in such manner that it will grip the butt of the willow, 30 draw it endwise through the stripping device and lay the successively stripped willows in parallelism with their butt ends pointing in the same direction.

Other objects and uses relating to specific 35 parts of the machine will be brought out in the following description.

In the drawings—

Figures 1 and 2 are, respectively, a top plan and a side elevation of a willow stripping machine embodying the features of 40 our invention.

Figure 3 is an enlarged detail sectional view taken on line 3—3, Figure 1.

Figure 4 is an enlarged detail sectional 45 view taken on line 4—4, Figure 2.

Figure 5 is an enlarged vertical sectional view of a portion of the machine taken on line 5—5, Figure 1.

Figure 6 is an enlarged horizontal sectional view, partly broken away, of the upper rear portion of the machine taken on 50 line 6—6, Figure 2.

Figures 7 and 8 are detail sectional views taken, respectively, in the planes of lines 55 7—7 and 8—8, Figure 5.

Figure 9 is an enlarged vertical sectional view taken on line 9—9, Figure 2.

Figure 10 is a top plan of the main portions of the cam levers of the gripping device.

As illustrated, this machine comprises a beater for loosening the bark on the butt end of the willow as the latter is fed thereto by hand and which may also serve as a supplemental stripping device; a main 65 stripping device for positively removing the bark; a gripping device for engaging the butt end of the willow and drawing it through the stripping device, and an oscillatory carrier for actuating the gripping 70 device and also for laying the stripped willows in parallelism with their butt ends pointing in the same direction.

The individual willows are fed by hand, 75 butt end foremost, through the supplemental stripper or beater where the bark on the butt end is at least loosened, the hand feed of the willow continuing until its butt end enters the main stripping device and is in position to be engaged by the gripper 80 which then automatically carries the willow forwardly through the stripping device, thereby removing the bark therefrom and releasing the stripped willow, whereupon the gripping device returns to repeat the operation upon the next succeeding willow.

The major portion of the machine is mounted upon a suitable supporting frame consisting, in this instance, of a pair of spaced upright standards —1— having their 90 lower ends secured to a suitable floor plate or base, and their upper ends connected by a yoke —3— having a rearwardly extending bracket —4—, the power device being mounted upon a separate frame consisting, 95 in this instance, of a pair of spaced upright standards —5— having their lower ends secured to a suitable floor plate or base —6—, as shown more clearly in Figures 1 and 2.

Supplemental stripper or beater.

This supplemental stripper or beater comprises a plurality of, in this instance four, steel brushes —7— mounted upon separate parallel shafts —8— which are journaled 105 in the end walls of a suitable casing or housing —9— and are provided with intermeshing gears —10—.

The shafts —8— are arranged symmetrically about a common center or axis, prefer- 110

ably at the four corners of a square, the brushes at diagonally opposite corners of the square constituting separate pairs having the peripheries of their steel bristles 5 traveling close to each other at the center of said square so as to cause the brushes to exert a beating contact with the entire periphery of the portion of the willow which may be registered therewith as it is being 10 fed by hand to the main stripping and gripping devices.

By arranging the brushes and their supporting shafts and gears in the manner described leaves a clear open space between 15 the peripheries of the gears through which the willows may be fed by hand, butt end foremost, across and between the peripheries of the brushes which produces the effect of loosening the bark preparatory to removing 20 by the main stripping jaws, hereinafter described, the individual willows being guided through suitable openings —11— and —12— centrally in the opposite end walls of the case or housing —9—, said openings 25 serving to guide the willow in its transit through the supplemental stripping device, and also to register its butt end with the main stripping device and grippers, the opening —12— being preferably elongated 30 by means of a tube —13— to further facilitate the guiding of the willow.

By guiding the willow in the manner just described as it is forced by hand through the supplemental stripping device prevents the 35 contact of said willow with the teeth of the gears —10—, while the rotation of the brushes in the direction indicated by arrows, Figure 8, causes them to act with opposing forces upon the periphery of the willow 40 which tends to hold the willow against turning while it is being fed between the brushes and facilitates greatly the freedom of feed of the willow through the supplemental stripper to the main stripping device.

45 In some instances, as in the treatment of willows with comparatively thin or light bark, these brushes may be used exclusively for the removal of the bark independently of the main stripping device, but where the 50 bark is rather thick and tough, the rotary beating operation of the brushes upon the periphery of the bark tends to loosen the same and assures the complete removal of the bark by the main stripping device, and 55 to this extent the supplemental stripper becomes a desirable adjunct to the machine.

On the other hand, if the bark of the willows is still green and reasonably soft, it 60 may be readily removed by the main stripping device, thus permitting the supplemental stripping device to be dispensed with and, therefore, we do not wish to limit our invention to the use of the supplemental stripper or beater.

65 When the supplemental stripper or beater

is used, it may be driven by an electric motor —14— through the medium of a belt —15— or by any other equivalent driving means.

Main stripping device.

70

As the willows are fed by hand through the guides, as previously described, the butt end thereof enters between a pair of opposed V-shape jaws —16— and —17— arranged to 75 form an opening —18— into which the butt end of the willow is fed, one of the jaws, as —16—, being rigidly secured to the yoke —3— near the center of the lower edge thereof, as shown more clearly in Figure 7, the 80 other jaw —17— being secured to a bracket —19— on a vertically movable rock arm —20— which is pivoted at —21— to the yoke —3— so as to move the jaw —17— toward and from the jaw —16—, and thereby cause 85 the meeting faces of said jaws to impinge against the periphery of the willow for removing the bark therefrom as said willow is drawn endwise through the jaws in a manner presently described.

The faces of the jaws are preferably covered with yielding stripper plates —22— of rubber or equivalent material capable of frictionally engaging and stripping the bark from the wood when the jaws are brought 95 to their pressing positions without liability of mutilating such wood when the willow is drawn endwise between the jaws, the stripping plates of each jaw being disposed at substantially right angles to each other and 100 in vertical planes side by side so that each side of each jaw will be disposed in the same vertical plane as and cooperate with the corresponding side of the other jaw, the opening between the jaws being normally rectangular or substantially square when open 105 so as to engage a maximum area of the periphery of the adjacent portion of the willow, which area is somewhat increased by the yielding of the stripping plates of the jaws when brought into pressing engagement with the willow, thereby stripping the entire bark from the wood as the willow is drawn through the jaws.

The means for operating the upper movable jaw —17— consists in addition to the lever —20— a bell-crank lever —23—, Figures 7 and 8, said bell-crank lever being pivoted at —24— to the yoke —3— and has one arm thereof provided with a roller —25— 120 for engaging the under side of the lever —20— and its other arm connected by a link —26— to a pedal lever —27—.

This pedal lever is fulcrumed at —28— to the floor plate or base —2— and is connected to the standard —1— by a retracting spring —29— which normally raises the free end of the pedal lever —27— to release the bell-crank lever —23— and allow the free end of the lever —20— to be rocked 130

downwardly by means of a link —30— and a retracting spring —31— which in turn is connected to an adjustable screw —32— by which the tension of the spring may be adjusted to operate the lever —20— for closing the upper jaw upon the willow with the desired degree of pressure.

The link —30— connects the upper end of the spring —31— with the free end of the lever —20—, the latter being guided in its vertical movement between a guide bar —32— and the adjacent face of the yoke —3— to which the guide bar is secured, as shown more clearly in Figures 6, 7 and 8.

15 *Movable abutment.*

In order that the butt end of the willow may be fed between the jaws a distance just sufficient to allow it to be gripped by the 20 gripping device, presently described, while the stripping jaws are still open preparatory to closing the jaws and drawing the willow between the same for stripping the bark therefrom, we have provided a vertically movable stop lever —33—, fulcrumed at —34— to the rear side of the yoke —3— and having one end formed with an abutment —35— movable across and a short distance to the rear of the opening —18— between the jaws into and out of the path of the butt end of the willow as the latter is forced between the stripping jaws, the opposite end of said lever being connected by a link —36— to the spring —31—, as shown 30 in Figure 2, so that the same spring may serve to simultaneously close the upper stripping jaw upon the willow and open or raise the abutment —35— out of the path of movement of the willow, whereupon the 40 gripping device, presently described, may be brought into engagement with the butt end of the willow and operated to draw said willow through the stripping device for removing the bark therefrom.

45 *Gripping device.*

The means for gripping the butt ends of the willows and drawing the latter through the stripping device comprises a pair of 50 opposed reversely arranged cam levers —37— disposed in the same horizontal plane at opposite sides of, but in proximity to, the path of movement of the willow as it is passed between the stripping jaws and against the abutment —35—, said levers being pivoted at —38— to a longitudinally movable frame —42— and provided with eccentrically disposed biting nibs —39— projecting from the inner edges thereof for 60 biting engagement with opposite sides of the butt end of the willow as the outer ends of the levers are rocked forwardly in a manner presently described, the inner ends of the levers —37— bearing the biting nibs —39— being disposed just at the rear of,

but in close proximity to, the limiting stop or abutment —35— so as to engage the willow as near the butt end thereof as possible after the latter has been forced against the abutment.

The outer ends of the levers —37— are connected by forwardly projecting links —40— to a longitudinally movable plate or cross head —41— which is slidably mounted in the frame —42— and has its 70 forward end connected by links —43— to a rocking carrier —44—, as shown more clearly in Figure 5, the frame —42— being connected by a link —45— to a longitudinally extending bar —46— forming a part 75 of the same carrier.

The link —43— is rigidly secured at two points —47— and —48— to the carrier —44—, while the link —45— is pivotally connected at —49— and —50— to the frame 80 —42— and bar —46—, respectively, and together with the frame —42— is spring-pressed rearwardly by a coil spring —51—, Figure 5.

It is now apparent that the links —43— and —45— constitute the only means of support for the sliding plate —41— and its supporting frame —42— and that if some means is provided for temporarily detaining the forward movement of the frame 90 —42— while the carrier —44— and plate —41— attached thereto is being moved forwardly, the cam levers —37— will be operated to approximately the position shown by dotted lines in Figure 6 to cause 100 the biting nibs —39— to engage the opposite side of the butt end of the willow, and that if then the frame —42— is released it, together with the plate —41—, will be carried forwardly to draw the willow through 105 the stripping device for removing the bark therefrom, and for this purpose we have provided the upper portion of the frame —42— with the rearwardly projecting spring arms —52— in sufficiently spaced relation transversely to receive between them a stationary detent —53— which is secured to and extends forwardly and downwardly from the central portion of the yoke —3—, as shown more clearly in Figures 5 110 and 7, said arms being united at their bases by an abutment —54— cooperating with the detent —53— to limit the return movement of the carrier to its normal position, shown in the drawings.

The free ends of the spring arms —52— are preferably flared laterally, but the portions of the springs adjacent the bases of the flaring portions are provided with in-turned shoulders —55— spaced a less distance than the diameter of the detent —53— so as to allow the detent to pass forwardly between them and to temporarily detain said detent from withdrawal between the shoulders until the force applied to the plate 125 130

—41— for drawing it forward is sufficient to overcome the tension of the spring arms tending to hold the plate against forward movement.

5 It is evident, however, that the movement of the frame —42— rearwardly would also effect the closing action of the biting nibs —39— upon the willow, the spring —51— being employed to produce this effect after 10 the spring arms —52— have been withdrawn from the detent —53— during the continued forward movement of the carrier —44— so as to maintain the grip of the nibs —39— upon the willow during the 15 stripping operation.

Carrier.

The carrier for operating the gripping device to draw the willow through the stripping device consists primarily of a circular drum —56— centrally journaled at —57— upon and between the standards —1— and provided with a substantially semi-circular peripheral section —58— channeled in cross 25 section to receive and retain the willow therein as the latter is drawn through the stripping mechanism, the peripheral length of the channeled section being somewhat greater than the maximum length of any 30 willow operated upon so that it may be used for stripping willows of any length.

This channeled section —58— normally extends from a point in the periphery of the drum near the top or approximately in 35 transverse alignment of the standards —1— rearwardly and downwardly to approximately the diametrically opposite point in said periphery, suitable means being provided for rotating the drum through substantially a half revolution and return to 40 complete the cycle of movement for the stripping of a single willow, although it is evident that any number of these devices may be arranged side by side and to operate 45 simultaneously or individually if desired without departing from the spirit of this invention.

The means for operating the drum —56— consists of a grooved pulley —59— secured 50 to the shaft —57— at one end of the drum and suitable cables, as —60—, wound entirely around the periphery of the pulley and having their ends extended in opposite 55 directions tangentially to the lower side thereof and attached to adjustable bolts —61— which are adjustably mounted in a sliding yoke —62— of a pitman —63—.

One end of the pitman —63— is adjustably connected to a crank arm —64— of a 60 driving shaft —65— which in turn is connected by means of sprocket wheels —66— and a belt —67— to the power-driven shaft —68— having a pulley or hand wheel —69— adapted to be connected to any available 65 source of power, not shown.

The yokes —62— are movable endwise against the action of coil springs —70— which are interposed between them and suitable collars —71— on the pitman —63— to assure the full movement of the drum 70 —56— from one extreme position to the other and return without liability of over-straining any part of the operating mechanism, the springs —70— serving to compensate for any excess movement of the 75 pitman in either direction beyond that which is necessary to effect movement of the drum between the limits referred to.

It is evident, however, that this movement of the drum may be closely regulated by 80 the adjustment of the pitman in the slotted crank arm —64— provided for that purpose.

At the end of movement of the drum —56— following the stripping operation of one of the willows, a pair of forwardly projecting spring arms —52'—, similar to the springs —52— and which are mounted upon the same abutment —54—, are brought into engagement with a stop pin —53'— similar to the detent —53—, except that it is 90 mounted upon the inner end of the pedal lever —27— and cooperates with the abutment —54— to limit the movement of the drum from its normal position to approximately a half revolution, the arms being also 95 provided with inturned shoulders —55— to frictionally engage the pin —53'— at the beginning of the return movement of the carrier and thereby cause the frame —42— to lag or rather to be temporarily held 100 against return movement sufficiently to open the gripping jaws —39— for releasing the willow and allowing it to fall from the channeled section —58— of the drum —44— on to the floor or underlying support so that the successively stripped willows will be stacked in parallelism with their butt ends lying pointing in the same direction and approximately in the same transverse vertical plane.

110 The relative lengthwise movement of the plate —41— and frame —42— is limited by an adjustable stop screw —75— which is mounted on the inner end of the plate —41— and adapted to engage the inner edge of the upper portion of the frame —42—, as shown more clearly by dotted lines in Figure 6.

115 The pitman —63— is guided in its endwise movement substantially tangential to the periphery of the pulley —59— by means 120 of a grooved roller —76— which is supported on the studs —77— on one of the upright standards —1—, as shown in Figure 9.

In operation, assuming that the pedal lever —27— is released and elevated by its 125 spring —29—, in which case the bell-crank lever —23— will be similarly released from engagement with the lever —20— through the medium of the link —26— allowing the spring —31— to close the upper stripping 130

jaw — 17 — and to raise the abutment — 35 —, thus allowing the gripping jaws — 39 — to pass under said abutment as the drum assumes its starting position shown in Figures 5 1 and 2.

At this time the pedal lever — 27 — is depressed to open the stripping jaw — 17 — and to simultaneously drop the abutment — 35 — to its operative position, whereupon 10 a willow is inserted by hand, butt end foremost, between the beater brushes — 7 — and through the guides — 11 —, — 12 — and — 13 — and thence between the stripping jaws — 16 — and — 17 — until its forward 15 end abuts against the abutment — 35 —, this forward advancing of the willow by hand being accomplished while the crank arm — 64 — is passing the dead center.

The upper side of the drum then begins 20 to advance forward which causes the gripping members — 39 — to grip opposite sides of the butt end of the willow by reason of the lag of the frame — 42 —, due to the engagement of the spring arms — 52 — with its 25 fixed detent — 53 — and to the forward draft of the link — 43 — upon the plate — 41 — which holds the gripping members in engagement with the butt end of the willow and draws the latter between the stripping 30 jaws — 16 — and — 17 — until the willow is stripped from end to end, the movement of the drum with the willow thereon continuing until the spring arms — 52 — and abutment — 55 — have encountered the stop pin 35 — 53' — on the pedal lever — 27 — which occurs at about the same time that the crank arm — 64 — has completed a half revolution, it being understood that this rocking motion is imparted to the drum by the cables 40 — 60 — around the pulley — 59 — and the tangential movement of the pitman — 63 — to which the cables are yieldingly connected through the medium of the springs — 70 — and sliding cross heads — 62 —.

45 Now, immediately following this operation of the drum through substantially a half revolution, as limited by the engagement of the abutment — 54 — with the stops — 53' — and just at the beginning of the 50 turn movement of the drum, the spring arms — 52 — which frictionally engage the pin — 53' — cause a slight lagging of the frame — 42 — sufficient to open the gripping jaws — 39 — and to allow the willow to drop 55 therefrom, whereupon the drum continues to return to its starting position until limited by the engagement of the abutment — 54 — with the detent — 53 — which assures the complete opening of the jaws ready to 60 receive the butt end of another willow for a repetition of the operation just described.

What we claim is:

1. In a willow stripping machine, a carrier movable about a horizontal axis, a stripping 65 device through which the willow is fed end-

wise butt-end first and provided with opposed willow engaging faces tangential to the arc of movement of the carrier, a gripping device in advance of the stripping device engaging the butt-end of the willow, a 70 support for the gripping device movable in the direction of feed of the willow and carried by the carrier, a slide on said support also movable in the direction of feed of the willow, means actuated by said carrier for 75 moving the slide along said support away from the stripping device, means actuated by the last named movement of the slide for closing the gripping device upon the butt-end of the willow. 80

2. In a willow stripping machine, the combination of a stripping device through which the willows are fed endwise butt-end first, a carrier movable in the direction of feed of the willows, gripping-jaws in advance of the stripping device for engaging the butt-end of the willows, a support for the gripping-jaws carried and supported only by the carrier, a slide movable along and upon said support, connections between 85 the carrier and slide for moving the latter along said support, means actuated by the slide for closing the jaws upon the willow, and connections between the slide and its support for moving the latter therewith 90 after the jaws have been closed upon the willow. 95

3. In a willow stripping machine, the combination of a stripping device through which the willow is fed endwise butt-end 100 foremost, a carrier movable in the arc of a circle in the direction of feed of the willow, said stripping device having opposed jaws extending tangentially to the arc of movement of the carrier, a plate supported by 105 and movable with the carrier, gripping jaws pivoted to said plate to move therewith and adapted to receive the butt-end of the willow between them after being inserted through the stripping device, a slide movable lengthwise of and upon the plate, connections between the slide and carrier for moving said slide relatively to the plate and away from the stripping device as the carrier is moved forwardly and connections between said 110 slide and gripping jaws for closing the latter upon the butt-end of the willow during said relative movement. 115

4. In a willow stripping machine, the combination of a stripping device through 120 which the willows are inserted endwise butt-end foremost, a carrier movable beneath the stripping device in the direction of movement of the willow, gripping-jaws in advance of the stripping device for engaging 125 the butt-end of said willow, a support for said jaws, yielding connections between said support and carrier to allow a limited forward movement of the carrier relatively to the support, a slide movable lengthwise of 130

- and upon the support, connections between the carrier and slide for moving the latter forwardly relatively to the support, means actuated by the slide for closing the gripping-jaws upon the willow, and connections between said slide and its support for moving them both together with the carrier after the gripping-jaws have been closed upon the willow.
- 5 10 5. In a willow stripping machine, the combination of a stripping device through which the willows are fed endwise butt-end foremost, a carrier movable in the direction of feed of the willow, gripping-jaws in advance of the stripping device for engaging the butt-end of the willow, a support for said gripping-jaws carried by and movable in the direction of movement of the carrier, a fixed support, an abutment mounted on the fixed support and movable to and from a position across the path of movement of the willow as the latter is fed through the stripping device to limit the movement of said willow through the stripping device preparatory to engagement by the gripping-jaws of the butt-end of the willow, a slide movable lengthwise of and upon the first-named support, means actuated by the carrier for moving the slide in advance of the movement of the support, means actuated by this last named movement of the slide for closing the gripping-jaws upon the butt-end of the willow and thereby to cause the support to move with the slide and carrier for drawing the willow through the stripping device.
- 15 20 30 35 6. In a willow stripping machine, the combination of a stripping device through which the willows are fed endwise with their butt-ends foremost, a carrier movable in the direction of feed of the willow through the stripping device, a fixed support, an abutment mounted on the fixed support and movable into and out of the path of movement of the willow as it is fed through the stripping device for limiting said movement, gripping-jaws between the abutment and stripping device for engaging the butt-end of the willow, a support for said gripping-jaws carried by and movable in the direction of movement of the carrier, yielding connections between the second named support and carrier to allow the latter to move a limited distance relatively to said second named support, a slide movable lengthwise of and upon the second named support, connections between the slide and carrier for causing said slide to move with the carrier relatively to said second named support, means actuated by the slide along the second named support for closing the gripping-jaws upon the willow and thereby to cause the second named support to move with the slide and carrier.
- 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 - ment of said support, means actuated by the slide for closing the jaws upon the willow and thereby to move the support with the carrier as the latter is moved forwardly.
- 5 10. In a willow stripping machine, a carrier movable about a horizontal axis and provided with a concentric bearing-face for the willow, a frame-bar extending across the periphery on and above the carrier, a stripping device mounted on said frame-bar directly over the peripheral bearing-face of the carrier, gripping-jaws for engaging the butt-end of the willow, means actuated by the carrier for closing the gripping-jaws 15 upon the willow and drawing the same through the stripping device and upon the peripheral bearing-face of the carrier, means for moving the carrier through an arc of sufficient length to reverse the willow end 20 for end, and means for automatically disengaging the jaws from the willow at the end of said arc of movement of the carrier.
11. In a willow stripping machine, the combination of a carrier movable about a horizontal axis and provided with a peripheral bearing-face for the willow, stripping-jaws supported directly over the top of the carrier and engaging a perceptible portion of the length of the willow along 25 straight lines tangential to the periphery of said carrier, a plate yieldingly mounted on the carrier in advance of the stripping jaws, gripping-jaws pivotally mounted upon said plate to grip the butt end 30 of the willow, and means actuated by the carrier for closing the gripping-jaws upon the willow and drawing the latter through the stripping device as the carrier is rotated about its axis, means for rotating 35 the carrier through a predetermined arc. and means for releasing the jaws from engagement with the willow at the end of movement of the carrier through said arc.
12. In a willow stripping machine, the combination of a carrier movable about a horizontal axis and provided with a peripheral bearing-face for the willow, means for rotating the carrier through a predetermined arc of movement, a stripping device 40 supported above and in close proximity to said periphery or bearing-face and engaging a perceptible portion of the length of the willow along straight lines tangential to said bearing-face, and means actuated by 45 said carrier for engaging and drawing the willow through the stripping device around and upon the periphery of the carrier, and means for causing the willow to be released from its gripping means at the end of the 50 arc of movement of the carrier.
13. In a willow stripping machine, the combination of a carrier movable about a horizontal axis and provided with a peripheral bearing-face for the willow, a stripping device supported above and in close 55 proximity to said bearing-face and engaging a perceptible portion of the length of the willow along straight lines tangential to said bearing-face, gripping-jaws in advance of the stripping device, a support for said jaws carried and supported by the carrier, a slide mounted on said support and operatively connected to the carrier to move therewith in advance of the movement of said support, connections between said slide and gripping-jaws for closing the latter upon the willow as the carrier is moved forwardly, and yielding connections between the support and the carrier to cause the support to move with the carrier after the gripping-jaws have been tightened upon the willow.
14. In a willow-stripping machine, the combination of a stripping device, a gripping device for engaging the end of the willow and drawing it through the stripping device, an oscillatory carrier for the gripping device, and means for actuating the carrier including a pulley, a pitman and a cable wound around the pulley and having its ends attached to the pitman.
15. In a willow-stripping machine, the combination of a stripping device, a gripping device for engaging the end of the willow and drawing it through the stripping device, an oscillatory carrier for the gripping device, means for actuating the carrier including a pulley, a pitman and a cable wound around the pulley and having its ends attached to the pitman, and yielding connections between the pitman and cable.
16. In a willow stripping machine, the combination of a pair of opposed V-shaped stripping jaws having their open sides facing each other for receiving a willow between them and engaging a perceptible portion of its length along straight lines, spring actuated means for moving one of the jaws toward the other to cause the jaws to frictionally engage the periphery of the willow under yielding pressure, and means for drawing a willow from between the jaws and gradually deflecting it from said straight lines as it is drawn through the jaws to buckle the bark and thereby assist the jaws in stripping said bark from the willow.
17. In a willow stripping machine, the combination of a pair of opposed V-shaped stripping jaws having their open sides facing each other for receiving a willow between them, and engaging a perceptible portion of its length along straight lines, spring actuated means for moving one of the jaws toward the other to cause the jaws to frictionally engage the periphery of the willow under yielding pressure, and means for drawing a willow from between the jaws and gradually deflecting it from said straight lines as it is drawn through the jaws to buckle the bark and thereby assist the jaws

in stripping said bark from the willow, and means operable at will for moving the jaw closing means against the action of the spring to open the movable jaw to permit a willow to be inserted between the jaws.

18. In a willow stripping machine, the combination of a drum rotatable about an axis and having a circular bearing face for the willow, a willow stripping device engaging a perceptible portion of the willow along straight lines substantially tangential to the circular bearing face of the drum, and a gripping device mounted on the drum for engaging and drawing a willow through the stripping device and means for rotating said drum with the gripping device thereon to draw the willow endwise through the stripping device.

19. In a willow stripping machine, the combination of a drum rotatable about an

axis and having a concentric bearing face for the willow, a stripping device engaging a perceptible portion of the willow along straight lines substantially tangential to the concentric bearing face, means for rotating the drum first in one direction and then in an opposite direction from and to a normal position of rest, means for automatically causing the gripping jaws to open when the drum is returned to its normal position, and for causing the gripping jaws to close upon the willow when the drum is moved from its normal position.

In witness whereof we have hereunto set our hands this 15th day of April, 1918.

MAURICE J. TOPP.
WILBUR G. MILLER.
